Charles E. Arnold, P.O. Box 4104,
Louisville, Ky. 40204

Filed Dec. 30, 1970, Ser. No. 26,698

Term of patent 14 years

Int. Cl. D27—03

U.S. Cl. D85—2 P

FIG. 1 is a perspective view of a combined cigarette holder, match holder and ash tray or similar article, showing my new design;

FIG. 2 is a left end elevational view;

FIG. 3 is a right end elevational view; and

FIG. 4 is a side elevational view, the opposite side being substantially a mirror image thereof except for the finger gripping recess in the cover.

Portions of the tray are shaded to indicate contrast in appearance.

I claim:

The ornamental design for a combined cigarette holder, match holder and ash tray or similar article, as shown and described.
